CLAIM

The ornamental design for a shoe sole, as shown and described.

DESCRIPTION

FIG. 1 is a rear perspective view of a shoe sole, showing my new design;

FIG. 2 is a front perspective view thereof;

FIG. 3 is a top view thereof;

FIG. 4 is a bottom view thereof;

FIG. 5 is a left side view thereof; and,

FIG. 6 is a right side view.

The broken lines and lightened surfaces they enclose illustrate portions of the shoe sole, which form no part of the claimed design.

1 Claim, 6 Drawing Sheets
